CLAIM

I claim the ornamental design for a lighting fixture, as shown and described.

DESCRIPTION

FIG. 1 is a front elevation of the light fixture showing the new design;

FIG. 2 is a rear elevation thereof;

FIG. 3 is a side elevation of the light fixture with the opposite side being a mirror image thereof;

FIG. 4 is a top plan view thereof;

FIG. 5 is a bottom plan view thereof; and,

FIG. 6 is a perspective view thereof.
